ELIHU THOMSON, OF LYNN, MASSACHUSETTS.

ELECTRO-MAGNETIC CUT-OFF.

SPECIFICATION forming part of Letters Patent No. 360,123, dated March 29, 1887.

Application filed August 25, 1886. Serial No. 211,857. (No model.)

To all whom it may concern:

Be it known that I, ELIHU THOMSON, a citizen of the United States, and a resident of Lynn, in the county of Essex and State of Massachusetts, have invented a certain new and useful 5 Electro-Magnetic Cut-Off Mechanism, of which the following is a specification.

The present invention relates to means for establishing and preserving the continuity of 10 an electric circuit—such as an arc-light line or other constant-current line—upon which incandescent lamps or other translators of electric energy are arranged in series with arc lamps or in series with other devices or other 15 incandescent lamps.

The invention is designed to provide for two contingencies which may arise following the rupture of the carbon of the incandescent lamp—*i. e.*, first, abnormally-high resistance 20 at that point of the circuit; or, second, abnormally-low resistance which sometimes follows the formation of a substitute path for the current from wire to wire when the current travels from wire to wire in the vacuum-chamber 25 of the lamp, as an arc *in vacuo*.

For the purpose of my invention I employ a magnet or solenoid, preferably the latter, wound with two coils, one in the main or line circuit and the other in a derived or shunt 30 circuit, around the incandescent lamp or other translator of electric energy. The core or armature of the magnet, when attracted, moves a contact, which closes a shunt-circuit around the incandescent lamp or other translator. 35 The magnet's coils are wound so as to oppose each other's action, forming a differential magnet. A rupture of the filament or carbon conductor of the incandescent lamp, or generally a sudden increase in the resistance of the 40 translator of electric energy, in whatever form it may be, causes an attraction of the core or armature and closing of the shunting contacts, which are thereafter retained closed by the coil in the main or line circuit. A considerable fall in the resistance will, as herein shown, 45 operate likewise.

In the accompanying drawings, Figure 1 shows one of the forms of an apparatus embodying my invention. Fig. 2 shows a more 50 complete arrangement. Fig. 3 is a detail view of the core and other modified devices. Fig. 4 is a modified disposition of parts. Fig. 5 is

a modified arrangement of a very compact design with an ordinary electro-magnet, not axial.

55

In Fig. 1 wires *a b* are supposed to be connected with a constant-current line or a source of electric currents of uniform volume nearly. From *a* a connection is carried through the main-line coil *D* of the differential magnet *A*, 60 and from it to one terminal of an incandescent lamp, *L*, (or such device,) as indicated. A connection is also made, as shown at *e*, to one of a set of contacts at *T*, carried by the core *C* of the differential magnet, which closes 65 the contact when attracted into the axis of the coil *D*. Coincident in axis with the main line *D* is a fine-wire coil, *K*, oppositely wound to the main-line coil *D*, and connected in derived circuit with the lamp *L*—that is, one end to *b*, 70 as shown at *c*, Fig. 1, the wire leading from the other terminal of said lamp, and the other end to its first-mentioned terminal, as shown at *d*. The wire *b* has also a connection, by the wire *f*, as shown, to the upper or fixed contact at 75 *T'*. A spring or springs, *S S*, are used to adjust the magnetic strength and support the core. A variable wire-resistance (shown at *v*) may be used to adjust the effect of main-line coil *D*, as by shunting it. The adjustment 80 must be such that, the windings *D* and *K* being opposed in direction, the core *C* will not be lifted when *L* is in place, and the current normal to the line passes from *a* to *b*. The contacts *T T'* will of course be open, the tendency of the main-line coil *D* to raise the core 85 *C* being neutralized, so far as mechanical lifting or raising of said core is concerned, by the inverse current traversing *K* in shunt to *L*. When, however, *L* loses its conducting- 90 power or becomes of very high resistance—as by wasting or rupture of its carbon—more of the current traverses the fine-wire coil *K*, whose magnetic power is thereby increased, and it then exerts not only a sufficient force 95 to neutralize the effect of opposing coil *D*, but a sufficient additional power to cause the core *C* to rise and close the contact at *T T'*. The current then passes from *a*, through the coil *D*, to the core, through *T*, (closed,) and to *b*, 100 the lamp *L* being thus shunted, and the contact *T* is now held closed by the coil *D* acting alone. It is advisable to make the core *C* of split tube or wire bundle, so that its magnet-

ism may be easily reversed; and it is well, also, to have the fit of the core to the inside of the coil or tube on which the coil is wound, so as to have a dampening or slowing effect upon the motions of the core, to prevent too sudden movements. A dash-pot might of course be added to this end. The closing of the contacts at T T' and shunting will also occur should the lamp-resistance fall abnormally, as by the establishment of an arc in the vacuous space from one leg of the carbon conductor to the other in L. At such time the fine-wire coil K loses a part of its neutralizing-power and the main-line coil D asserts its supremacy, attracts the core, and shunts the apparatus, as before, through T.

In Fig. 2 a switch, W, is shown, by which a short-circuit connection may be made at will from a to b, so as to light or extinguish the lamp L at will. The main-line coil D is arranged as before, and the fine-wire coil K, wound around the lower end of the magnet, is located, as before, in a shunt around the lamp L. The core C, however, instead of being hung by a spring, rests on a plate-spring, S, which just supports said core, leaving the contact at T open. The contact at T is preferably assisted in closing by a small permanent or other magnet, M, very weak in power, placed so that when the core C rises the spring S, relieved of its weight, brings a piece of iron, N, carried thereby, near to the magnet M, resulting in a slight attraction. This magnet helps to keep the contact T closed during a very small interval of time, which may be needed for the core C to reverse its magnetism after the fine-wire coil K has lifted it, and the main-wire coil D is to hold it up, as described in connection with Fig. 1. In all other respects the same actions take place as with Fig. 1.

In Fig. 3 the core C is shown constructed as a fairly-fitting plunger entering the bobbin E, upon which the coils D and K are wound. The upper end of the bobbin E is closed, and the core so arranged has the effect of a dash-pot, and is useful in preventing the too sudden movements of the parts. The core C is also shown almost counterbalanced by a weight, S', instead of springs, as in Figs. 1 and 2. A link, l, connects the core C to the contact mechanism. The link has a small slot in its lower end, in which a pin on the contact-lever F has free play to a limited extent. The contact-lever bears a lower contact at T, and is pivoted so that a spring, M', may exert its force on a pin, N, in said lever on either side of a dead-center, according to the throw given by the core C and link l. The slot in the link l is of sufficient length to allow free play to the contact-lever F in closing contact at T. Thus when the core C rises the link l lifts the lever F. The spring M' is thrown above the dead-center, when it imparts a sudden upward movement to the outer end of the lever F, near the contact, resulting in a sudden closure at T. When the core begins to descend, it can have

no effect to open the contact at T until the upper end of the slot in l bears on the pin in F. This allows a certain amount of free play to the core C, during which time it will not affect the contact at T. Ample opportunity for reversal of magnetism, as before described, is thus secured, and during such reversal the core C virtually remains attracted, inasmuch as it may fall slightly, but in doing so does not open T.

In Fig. 4 the core C is made to carry the fine-wire coil K in its movements, its weight and that of the core being balanced by a spring, S, bearing the contacts T normally open. Its operation is the same as in Fig. 1, though not so perfect.

In Fig. 5 the axial magnet is replaced by an electro-magnet whose core is wound with the two coils D K differentially, and the armature C is arranged to be attracted and held to close the contact T when either winding preponderates in effect. A spring-retractor, S, though not necessary, may assist in adjustment, in virtually adding to the weight of the armature itself. A dash-pot, G, with oil or glycerine, may be employed to check sudden or vibratory movements of the armature C. The operation and connections are substantially as in the preceding figures, excepting that movements of the core are replaced by those of an electro-magnet armature.

It is to be understood that other forms of differential magnet may be substituted for those shown, provided the form selected permits either coil to preponderate under the described conditions, and thus close a contact which shunts the current around the lamp.

I am aware that cut-off devices have been wound with fine and coarse wire, the fine wire being connected in derived circuit around a lamp or other resistance and the coarse wire only thrown into action upon the closure of the contact, or, when kept in circuit, cut out by the closure of a contact upon retraction of the core or armature.

In my invention it is essential that the cut-off contact be closed by either coil acting singly or by the preponderating coil when they act together. It is also a feature of my invention that that coil which is in the main circuit at all times retains the core uplifted and keeps the contact closed, unless sufficiently opposed by the fine-wire coil K, and that when the core has been lifted by the fine-wire coil a reversal of magnetism takes place in the core, due to the reverse winding of the coarse or main-circuit coil and subsequent retention of the core in a lifted state, with retention of contact by said coarse coil acting alone.

In this specification I have described my invention in connection with a system of electric lamps; but it is evident that it may be used wherever the same conditions occur, as in an electric motor or other translator of electrical energy. I do not limit myself, therefore, to a cut-out for incandescent lamps; but

What I do claim is—

1. The combination, with an incandescent lamp, electric motor, or other translator of electric energy, of a coil in the main or leading circuit to such translator, a coil in a derived circuit of approximately constant resistance around the translator, a shunt around the translator, and a device responding to the differential action of such coils and adapted to close such shunt when either coil preponderates in power, and to keep such shunt closed thereafter by the power of the main-line coil, as and for the purpose described.

2. In an incandescent lamp, the combination of a coil in the main or feeding circuit, a coil in a derived circuit of approximately constant resistance around the lamp, and a core or armature or equivalent magnetic device responding to the differential action of such coils, whereby it is adapted to close a shunting contact around the lamp when either coil preponderates in power, and to retain such contact closed by the action of the coil in the main or leading circuit, as and for the purpose described.

3. In an incandescent lamp, the combination of a coil in a main-line or feeding circuit, an oppositely-wound coil in a derived circuit of approximately constant resistance around the lamp, such coils being substantially balanced in their magnetic effect upon the armature, core, or equivalent device under normal conditions of current and resistance, and which attract such armature or core and close such shunt upon the preponderance of either coil, due to abnormally high or low resistance in the lamp, as and for the purpose described.

4. In an incandescent lamp, the combination of a coil in the main or feeding circuit, an oppositely-wound coil of high resistance and of approximately constant resistance in a derived circuit around the lamp, and a device responding to the differential action of such coils, and adapted to close a shunt around the lamp when either coil preponderates in effect and to keep such shunt closed by the power of the main-line coil, as and for the purpose described.

5. In an incandescent lamp, the combination of a differential magnet with coils in the main circuit and in a derived circuit of approximately constant resistance around the lamp, a suspended core or armature, or equiv-

alent device, so adjusted as to be indifferent to such differential magnet under normal conditions of current and resistance, and to close a shunt around the lamp upon the preponderance of either coil, due to abnormally high or low resistance within the lamp, as and for the purpose described.

6. In an incandescent lamp, the combination of a coil in the main circuit of approximately constant resistance, a coil in derived circuit about the lamp, an armature, core, or equivalent device, and a contact mechanism in shunt to the terminals of the lamp, said armature being nearly balanced under normal conditions of current and resistance and adapted to close such contact mechanism upon a preponderance of magnetic strength in either coil and to keep such contact closed by the magnetic strength of the main coil, as and for the purpose described.

7. In an incandescent lamp, the combination of a differential magnet, a core, armature, or equivalent device, a contact mechanism, and a contact-retaining mechanism to hold such contact mechanism closed during the reversal of polarity of such magnet and pole, as and for the purpose described.

8. In an incandescent lamp, the combination of a differential magnet, a core, armature, or equivalent device, a contact mechanism which is closed by preponderance of either coil and then held closed by the action of a certain one of them, and a contact-retaining mechanism to hold such contact mechanism closed during reversal of polarity of the magnet and core, as and for the purpose described.

9. In an incandescent lamp, the combination of a differential magnet, a core, armature, or equivalent device, a contact mechanism controlled thereby, and means for checking the sudden movements of said core, armature, or equivalent device upon reversal of polarity of such magnet and core, as and for the purpose described.

Signed at Lynn, in the county of Essex and State of Massachusetts, this 19th day of August, A. D. 1886.

ELIHU THOMSON.
